FEEDING MECHANISM FOR SEWING MACHINES

Frank A. Kucera, Chicago, Ill., assignor to Union Special Machine Company, Chicago, Ill., a corporation of Illinois

Application February 19, 1937, Serial No. 126,585

19. Claims. (Cl. 112—215)

This invention relates to feeding mechanism for sewing machines, particularly for sewing machines of the type wherein the work support is tubular, as, for example, in what are known as feed-off-the-arm sewing machines.

Due to inaccuracies in the machining of the feed bars or of the directly associated parts of the actuating mechanism, the feed dogs often fail to register properly with the openings provided for them in the throat plates or are out of level transversely of the direction of feed. Under such conditions, the feed dogs will not progress the fabric uniformly with consequent production of crooked seams. Moreover, in feed-off-the-arm machines, the feed dogs are usually in the form of cantilevers reaching forwardly beyond the ends of the feed bars, and are thus not directly supported from beneath for capacity to react upon the presser feet with an equal degree of resistivity throughout their fabric contact areas.

My invention has for one of its aims to overcome the above drawbacks, which objection I realize in practice as hereinafter more fully disclosed, through provision of a feed bar whereof the forward end is of open yoke-like construction and overreaches the complementary stitch forming instrumentalities that cooperate with the needle or needles of the sewing machine beneath the throat plate; and through provision of a feed dog which overlies the open forward end of the feed bar and which is supported with capacity for separate vertical adjustment at its opposite ends, as well as with capacity for angular adjustment transversely of the direction of feeding.

Another aim of my invention is to insure against deflection and bending of the needle or needles during the period of their coaction with the complementary stitch forming instrumentalities, which objective I also attain in practice as hereinafter more fully disclosed, through provision of a guard, which, like the feed dog, is supported with capacity for adjustment on the feed bar.

Other objects and attendant advantages will appear from the following detailed description of the attached drawings, whereof Fig. I is a fragmentary view partly in side elevation and partly in longitudinal section of a feed-off-the-arm sewing machine embodying my invention.

Fig. II is a longitudinal sectional view of the tubular work supporting arm of the machine in which the feed and the looper mechanisms are housed.

Fig. III shows the work supporting arm in plan

with its top and end covers removed to expose the feed mechanism.

Fig. IV shows the feed bar and the feed dog supported thereby, in end elevation.

Fig. V is a detail sectional view, taken as indicated by the arrows V—V in Fig. II.

Figs. VI, VII and VIII are cross sections taken as indicated respectively by the arrows VI—VI, VII—VII and VIII—VIII in Fig. II.

Fig. IX is a fragmentary plan sectional view, taken as indicated by the arrows IX—IX in Fig. II.

Fig. X is a detail sectional view, taken as indicated by the arrows X—X in Fig. IX.

Figs. XI and XII are perspective views of the feed dog and the needle guard respectively.

Fig. XIII is a perspective view of a bracket piece by which the needle guard is adjustably supported on the feed bar.

Fig. XIV is a fragmentary view in side elevation of a modified form of feed bar and feed dog; and

Fig. XV shows the front end elevation of the modified feed bar and feed dog.

The sewing machine chosen for convenience of illustrating the present improvements is of the feed-off-the-arm type, generally similar in construction to the sewing machine featured in U. S. Patent No. 1,741,095, granted to Norman V. Christensen and Harold J. Le Vesconte on

March 24, 1929. As shown, the machine has a frame with a horizontal upper member 1 in which a rotary drive shaft 2 is journaled, and with a tubular work supporting arm 3 which is secured, by means of screws 4 (Fig. I) to a pendant hollow projection 5 at one end of said upper member.

The work supporting arm 3 extends horizontally forward from the region of its connection to the member 1, and to the top of its free end is secured a throat plate 6 by means of screws 7, see Fig. VI.

The end section 8 and the cover section 9 of the arm 3 are removable so that access may be had to the parts within. Centrally of the work-supporting arm 3 is a longitudinal rock shaft 11, which, near its ends is journaled in bearings 12 and 13.

Secured to the front end of the rock shaft 11 is a carrier 14 for a plurality of concentrically curved loops 15 (in this instance, three) that cooperate beneath the throat plate 6 with as many needles 16 upon penetration

of the latter down through the fabric (not shown) in a well known manner. The needles 16 are, of course, actuated in timed relation with the movements of the loops 15 by suitable mechanism, not illustrated, connected to the drive shaft

45

40

45

50

55

55

2 within the upper member 1 of the machine frame. The rock shaft 11 is oscillated as a consequence of the coordination of a ball crank 17 (Figs. II and III) at its rear end with the strap rod 18 of an eccentric (not shown) on the drive shaft 2 of the machine, for the purpose of imparting the necessary loop-taking and shedding movements to the loopers 15. The rock shaft 11 is also reciprocated endwise, such movement being imparted to it from a rocker 19 through a pitman 20 which has a ball pivot connection 21 at one end with said shaft and a similar connection 22 at its other end with a pendant arm 23 of said rocker. From Figs. II and III, it will be seen that the rocker 19 is mounted for oscillation about a transverse shaft 25 whereof the ends are fixed by set screws 26 in bosses 27 at opposite sides of the work supporting arm 3 of the machine frame. As shown in Fig. II, the rocker arm 23 has a longitudinal slot 28 along which the ball pivot 22 can be shifted to adjust the axial throw of the shaft 11. The rocker 19 is actuated from another eccentric 29 on the drive shaft 2, the associated strap rod 30 having a ball pivot connection at 31 with a horizontal arm 32 of said rocker.

The feed bar of the machine designated by a numeral 33 lies horizontally over the shaft 11 within the hollow of the work supporting arm 3, and is supported at an intermediate point immediately inward of the bearing 12, by a pair of links 34. At their lower ends these links 34 are pivotally connected to the front end of a lever 35 which is fulcrumed on a shaft 36 extending transversely of the work supporting arm 3 with its ends fixed in bosses 37 at opposite sides of said arm (see Figs. II and III). At its rear end, the lever 35 has a ball connection 39 with the strap rod 40 of a third eccentric 41 on the drive shaft 2. By the means just described, rise and fall movements are imparted to the feed bar 33, which also receives horizontal to and fro or feed movements by virtue of the connection of its rear end to a rocker 42 mounted for oscillation about another transverse shaft 43 whereof the ends are suitably journaled in bosses 44 at the sides of the work supporting arm 3, see Fig. VIII. The rocker 42 depends for its actuation upon the rocker 19 to an upward arm 45 of which it is connected by a pitman 46. As shown, the rocker arm 45 has an arcuate slot 47 concentric with the front pivot 48 of the pitman 46 along which slot the rear pivot 49 of said pitman can be shifted to adjust the feed movement of the feed bar and in turn the length of the stitch produced by the machine.

In accordance with my invention, the forward end 50 of the feed bar 33 is of a yoke-like construction and overreaches the loopers 15, said end being of angular cross section as will be observed from Fig. VII and having an opening 51 in its top and an opening 52 in its side for clearance of the loopers. The yoke-like portion 50 of the feed bar 33 is moreover formed centrally of its front end with a pendant projection 53.

Extending rearwardly over top of the yoke-like portion 50 at the free end of the feed bar 33 is a bridging feed dog 54 which is likewise of open construction (see Fig. XI) and which has toothed ridges projecting upward through a correspondingly shaped slot 55 in the throat plate 6. At its front end, the feed dog 54 has a pendant tongue 56 which engages a vertical groove 57 in the front face of the pendant end projection 56 of the feed bar 33. As shown in Figs. IV and X, the tongue 56 has a longitudinal clearance slot 58 for the

shank of the cap screw 59 which engages a threaded hole 60 in the projection 53, as a consequence of which the feed dog 54 can be vertically-adjusted at its front end relative to the feed bar 33. From Fig. II, it will be noted that the rear end of the feed dog 54 rests on a screw stud 61 which is adjustable in the top of the feed bar 33. The feed dog 54 is thus firmly and effectively supported from beneath and able to resist the pressure of the presser foot (not illustrated) of the machine uniformly throughout its contact area without yielding to flexure.

In order to guide and brace the needles 16 at the time that they cooperate directly with the loopers 15 beneath the throat plate 6 incident to stitch formation, I have provided a guard 62 which is separately illustrated in perspective in Fig. XII. As shown, this guard 62 has a plurality of bevel sided fingers 63 for engagement by the needles 16 respectively, and a horizontal shank 64 adapted to fit a groove or recess 65 in the horizontal top extremity 66 of an angular supporting bracket piece 67 which is separately illustrated in perspective in Fig. XIII. A cap screw 68 (Figs. IX and X) with its shank passing through a longitudinal slot 69 in the shank of the guard 62 and engaging a tapped hole 70 in the top of the bracket piece 67, serves to secure said guard to the bracket piece at a level immediately below the ends of the loopers 15 (Fig. VII). The pendant portion 71 of the bracket piece 67 in turn fits a vertical slot at the back of the pendant projection 53 on the feed bar 33, whereto it is secured by a cap screw 73, the shank of which passes through a vertical slot 74 in said projection and engages a tapped hole 75 in said bracket piece, see Figs. II, IV, V, IX and X. This arrangement permits both vertical and horizontal adjustment of the guard 62 in respect to the feed bar 33 so that perfect operative coordination between the needles 16 and the loopers 15 may be secured. The guard 67, it will be noted from Figs. IX and X, is readily accessible for adjustment through the top and side openings 51 and 52 of the yoke-like portion 50 of the feed bar 33.

In the modification featured in Figs. XIV and XV, the slot 57a in the front of the pendant projection 53a of the feed bar 33a is considerably wider than the tongue 56a of the feed dog 54a so that the latter can be adjusted angularly about the cap screw 59a as well as vertically. Set screws 78 bearing against the opposite side edges of the tongue 56a below the cap screw 59a are relied upon to prevent displacement of the feed dog 54a in angularly adjusted positions. By virtue of the construction just described, the feed dog 54a can obviously be properly leveled transversely of the direction of feeding and centralized within the opening 55 of the throat plate 6 in compensating for inaccuracies in the machining of the feed bar 33, the feed lift lever 35, etc.

Having thus described my invention, I claim:

1. Feeding mechanism for sewing machines comprising a feed bar; means for imparting to and fro and up and down movements to the bar; a feed dog with its forward end secured with capacity for vertical adjustment to the forward end of the feed bar and extending rearwardly over the top of said bar; and means vertically adjustable on the feed bar whereon the rear end of the feed dog rests.

2. Feeding mechanism for sewing machines comprising a feed bar; means for imparting to and fro and up and down movements to the bar; an overlying feed dog with a pendant tongue at

- one end secured with capacity for vertical adjustment to the front end of the feed bar; and means vertically adjustable in the top of the feed bar for supporting the other end of the feed dog.
3. Feeding mechanism for sewing machines comprising a feed bar; means for imparting to and fro and up and down movements to the bar; an overlying feed dog with a longitudinally slotted pendant tongue at one end; a cap screw with its shank passing through the slot of the tongue and engaging into the end of the feed bar; and a screw stud adjustably engaged in the top of the bar for supporting the other end of the feed dog.
10. Feeding mechanism for sewing machines comprising a feed bar; means for imparting to and fro and up and down movements to the bar; a feed dog with a pendant longitudinally slotted tongue; a cap screw with its shank passing through the slot of the tongue and engaging into the end of the feed bar, so that said dog can be adjusted vertically; and means whereby the tongue can be moved about the screw as an axis to angularly adjust the dog laterally of the direction of feeding.
15. Feeding mechanism for sewing machines comprising a feed bar; means for imparting to and fro and up and down movements to said bar; a feed dog with a pendant tongue pivotally connected to the end of the feed bar to permit angular adjustment of the feed dog laterally of said bar; and set screws engaged in the bar and adapted to bear against opposite sides of the tongue beyond the pivotal connection to hold the dog against displacement in angularly adjusted positions.
20. Feeding mechanism for sewing machines comprising a feed bar; means for imparting to and fro and up and down movements to the bar; a feed dog with a pendant longitudinally slotted tongue; a cap screw with its shank passing through the slot of the tongue and engaging into the end of the feed bar whereby said dog can be adjusted both vertically and angularly relative to said bar; and set screws engaged in the bar and adapted to bear against opposite sides of the tongue beyond the cap screw to hold the dog against displacement in angularly adjusted positions.
25. Feeding mechanism for sewing machines comprising a feed bar; means for imparting to and fro and up and down movements to the bar; a feed dog with a pendant longitudinally slotted tongue; a cap screw with its shank passing through the slot of the tongue and engaging into the end of the feed bar; and means for imparting to and fro and up and down movements to the feed bar.
30. Feeding mechanism for sewing machines comprising a feed bar; means for imparting to and fro and up and down movements to the bar; a feed dog with a pendant longitudinally slotted tongue; a cap screw with its shank passing through the slot of the tongue and engaging into the end of the feed bar whereby said dog can be adjusted both vertically and angularly relative to said bar; and set screws engaged in the bar and adapted to bear against opposite sides of the tongue beyond the cap screw to hold the dog against displacement in angularly adjusted positions.
35. Feeding mechanism for sewing machines comprising a feed bar; means for imparting to and fro and up and down movements to the bar; a feed dog with a pendant longitudinally slotted tongue; a cap screw with its shank passing through the slot of the tongue and engaging into the end of the feed bar; and means for imparting to and fro and up and down movements to the feed bar.
40. Feeding mechanism for sewing machines comprising a feed bar with a vertical opening adjacent its forward end; a feed dog bridging said opening; means whereby the feed dog is secured at its outer end with capacity for vertical adjustment relative to the bar; a screw stud adjustable in the top of the feed bar for supporting the inner end of said feed dog; and means for imparting to and fro and up and down movements to the feed bar.
45. Feeding mechanism for sewing machines comprising a feed bar with a vertical opening adjacent its forward end; a feed dog bridging said opening; means whereby the feed dog is secured at its outer end with capacity for vertical adjustment laterally of the direction of feeding; and means projecting up from the feed bar to form a rest for the other end of the dog.
50. Feeding mechanism for sewing machines comprising a feed bar; means for imparting to and fro and up and down movements to the bar; a feed dog on the feed bar pivotally connected at one end to the bar with capacity for angular adjustment laterally of the direction of feeding; and means projecting up from the feed bar to support the rear end of the dog.
55. Feeding mechanism for sewing machines comprising a feed bar; means for imparting to and fro and up and down movements to the bar; a feed dog pivotally connected to the end of the feed bar with capacity for angular adjustment laterally of the direction of feeding and reaching rearwardly over the bar; and means projecting up from the bar for supporting the rear end of the dog.
60. Feeding mechanism for sewing machines comprising a feed bar; means for imparting to and fro and up and down movements to the bar; a feed dog extending rearwardly over the top of the bar and having a vertically-slotted pendant shank; a securing screw passing through the slot and engaging into the end of the bar, whereby the dog may be adjusted vertically and also angularly crosswise of the direction of feeding about the screw as an axis; and means vertically adjustable on the bar for supporting the rear end of the feed dog.
65. Feeding mechanism for sewing machines comprising a feed bar; means for imparting to and fro and up and down movements to the bar; a feed dog extending rearwardly over the top of the bar and having a vertically-slotted pendant shank; a securing screw passing through the slot and engaging into the end of the bar, whereby the dog may be adjusted vertically and also angularly crosswise of the direction of feeding about the screw as an axis; and means vertically adjustable on the bar for supporting the rear end of the feed dog.
70. Feeding mechanism for sewing machines comprising a feed bar; means for imparting to and fro and up and down movements to the bar; a feed dog extending rearwardly over the top of the bar and having a vertically-slotted pendant shank; a securing screw passing through the slot and engaging into the end of the bar, whereby the dog may be adjusted vertically and also angularly crosswise of the direction of feeding about the screw as an axis; and means vertically adjustable on the bar for supporting the rear end of the feed dog.
75. Feeding mechanism for sewing machines comprising a feed bar; means for imparting to and fro and up and down movements to the bar; a feed dog extending rearwardly over the top of the bar and having a vertically-slotted pendant shank; a securing screw passing through the slot and engaging into the end of the bar, whereby the dog may be adjusted vertically and also angularly crosswise of the direction of feeding about the screw as an axis; and means vertically adjustable on the bar for supporting the rear end of the feed dog.

17. In a sewing machine having a vertically-reciprocating needle and a complemental stitch-forming element cooperating with the needle; feeding mechanism including a horizontal feed bar with a vertical opening through which the complemental stitch-forming element projects, and a feed dog bridging the opening in the feed bar over said complemental stitch-forming element.
18. Feeding mechanism for sewing machines including a feed bar and a feed dog carried thereby; means for imparting to and fro and up and down movements to the feed bar; means whereby the feed dog is secured to the bar with capacity for vertical adjustment; and separate means for engaging the feed dog at a right angle to the
- securing means whereby it may be adjusted on the feed bar transversely of the direction of feeding and fixed in such adjustment.
19. Feeding mechanism for sewing machines including a feed bar and a feed dog carried thereby; means for imparting to and fro and up and down movements to the feed bar; separate means whereby the feed dog is pivotally secured to the feed bar with capacity for up and down and angular adjustment transversely of the direction of feeding; and separate regulatable means for engaging the feed dog at a right angle to the securing means to fix said dog in its transversely adjusted positions.

FRANK A. KUCERA. 15
